UNITED STATES PATENT OFFICE.

ANTON C. FONS, OF ROYAL OAK, MICHIGAN, ASSIGNOR TO S. J. FONS, OF ROYAL OAK, MICHIGAN.

TRY-SQUARE.

1,287,943.

Specification of Letters Patent. Patented Dec. 17, 1918.

Application filed September 12, 1916. Serial No. 119,715.

To all whom it may concern:

Be it known that I, ANTON C. FONS, a citizen of the United States, residing at Royal Oak, in the county of Oakland and State of Michigan, have invented new and useful Improvements in Try-Squares, of which the following is a specification.

This invention relates to try squares for carpenters' use, and it has for its object to produce a simple and efficient try square of improved construction which will be provided with means for marking ceiling, flooring and other material that is to be cut in such a manner that the mark will be absolutely plain and ineradicable.

A further object of the invention is to produce a simple and efficient try square including a slidable member and a marking saw which may be applied to said slidable member for the purpose of marking lumber that is to be cut in certain lengths and at certain angles.

With these and other ends in view which will readily appear as the nature of the invention is better understood, the same consists in the improved construction and novel arrangement and combination of parts which will be hereinafter fully described and particularly pointed out in the claim.

In the accompanying drawing has been illustrated a simple and preferred form of the invention, it being, however, understood that no limitation is necessarily made to the precise structural details therein exhibited, but that changes, alterations and modifications within the scope of the claim may be resorted to when desired.

In the drawing,—

Figure 1 is a top plan view of the improved try square.

Fig. 2 is a bottom plan view of the same.

Fig. 3 is a top plan view with the cover plate detached.

Fig. 4 is a transverse sectional view taken on the line 4—4 in Fig. 1.

Fig. 5 is a plan view of the square as it appears when the marking device has been detached.

Corresponding parts in the several figures are denoted by like characters of reference.

The improved try square comprises a body portion 15 and a blade 16, the latter being securely attached to the body portion at a right angle to the same, one side of the body portion being, however, provided with an

extension forming a shoulder 17 which lies at an angle of 45 degrees to the blade, thus enabling the try square to be utilized for making a straight or a mitering mark.

The blade portion of the device is provided with a recess 16' to accommodate a slide 19 having shoulders or offsets 20, whereby its movement will be limited, said shoulders being adapted to engage or contact with abutments 17' on the blade at the limits of the movement of the slide. A depression or pocket 18 is formed within the confines of the recess 16'. The slide is confined within the recess 18 by means of a detachable cover 21 having a slot 22 through which protrudes a handle 23 that is pivotally connected with the slide for manipulating the same, so that when not in use the said handle may be folded within the confines of the slot 22. Said handle, therefore, occupies no appreciable space when the device is packed in a tool chest or other storage place. The longitudinal outer edge of the slide 19 registers with the outer edge of the blade 16, and connected securely with said outer edge of the slide 19 is a saw blade 24, the same being secured upon the slide by means of a clamp member 25 and set screws 26. By reciprocating the slide it will be seen that the saw blade may be reciprocated in a line coinciding with the outer edge of the blade 16, it being understood that the teeth of the marking saw will be proportioned to extend slightly below the blade 16. It will also be understood that the position of the saw blade may be reversed so as to enable it to be used in connection with either side of the try square for making straight or mitering marks, as required. The pocket 18 may be utilized as a receptacle for said blade which will thus be readily available in case the one mounted on the slide should become dull or broken.

The cover plate 21 is provided at one corner with a sharp edged arcuate projection 27, see Fig. 1, which may be utilized for making a mark on the face of the lumber that is to be cut to indicate the line that is to be marked, thereby avoiding the use of a carpenter's pencil.

From the foregoing description, taken in connection with the drawing hereto annexed, the operation and advantages of this invention will be readily understood by those skilled in the art to which it appertains. The construction of the improved device 110

is very simple and inexpensive. By properly proportioning the parts the recess 18 may be utilized as a pocket or receptacle in which the saw blade and the attaching 5 means for the same may be stored when not in use.

Having thus described the invention, what is claimed as new, is:—

A try square comprising a body portion, a 10 blade having a recess opening through one side thereof only, limiting abutments adjacent to the ends of said recess, a slide in said

recess having its outer edge in registry with the longitudinal outer edge of the blade and formed with offsets to engage the abutments 15 in the respective limits of movement of the slide, a saw blade mounted detachably on the edge of the slide, a cover plate secured detachably on the blade to cover the open side of the recess and having a slot, and a 20 handle pivoted on the slide and foldable within the confines of the slot.

In testimony whereof I affix my signature.
ANTON C. FONS.
